PLUGBOARD ASSEMBLY

Clayton E. Campbell, Jr., Greensboro, N.C., assignor to Cam Corporation, Greensboro, N.C., a corporation of North Carolina

Filed Apr. 20, 1966, Ser. No. 543,902
12 Claims. (Cl. 339—18)

ABSTRACT OF THE DISCLOSURE

A patchcord system which is utilized in connection with electrical accounting machines, computers and the like, having front and rear bays carrying plugwires and mating contact springs, the bays pivotally connected for cooperative electrical connection between the plugwires and springs. A cam is employed to insure reliable electrical conductivity between the plugwires and the springs, and the system may be shielded alternatively by a novel shielding means if desired.

It has become the prevailing practice to provide in electrical accounting machines, computers and the like, a fixed panel on which are arranged a group of electrical contacts in rows and columns, certain of these contacts being connected to the sensing elements of the machine or mechanism and the remainder providing terminals for the leads connected to the instrument panels that perform the operative functions of the machine. A control or movable panel is also provided which cooperates with the fixed panel to furnish circuit connections between the contacts associated with the sensing elements and the instrumentalities desired to be operated according to some predetermined arrangement. Conventionally, the control or movable panel is adapted to be detached from the assembly for the purpose of interchanging such panels whenever a variation of circuit connections or arrangements is desired, it being common practice to provide a pre-set control panel for each of the circuit arrangements periodically desired to be set into the machine whereby a particular group of computations may be similarly handled in accordance with certain standard reports to be rendered by the machine.

It has been found the desired mode of system construction to support the control panel within a frame which may be pivotally connected to the fixed panel, the pivotal displacement of the frame juxtaposing the panels into a parallel and operative relationship. To distribute evenly the contact pressure throughout the assembly whereby warping of the control panel is prevented, it is preferable that the panels, or plugboards, first be brought to a parallel position with the two sets of contacts being in an overlapping equally spaced relationship. Subsequent movement of the movable panel parallel to and along the fixed panel causes the contacts to engage simultaneously with an even distribution of pressure.

To render such a plugboard assembly practical, good electrical contact between the panels must be insured. It has been found, however, that merely bringing the control panel plugs into direct engagement with the fixed panel terminals or numbers does not result in good electrical contact because, among other reasons, the accumulation of dust and films on the contacts induces corrosion and pitting of the contact surfaces when these are not abraded in some consistent and effective manner.

In a conventional plugboard assembly or system, up to several hundred contact elements can be located on each board in a minimum area with a minimum spacing between rows and columns. As a result, where the board is formed from an insulating material, current leakage can occur between contacts producing a more or less

2

detrimental effect on the operation of the machine according to its character. For example, in an analog computer, information is generally represented by voltage pulses or levels which are compared for resolution to a

5 fixed reference level on the basis of relative magnitude. Any significant leakage between contacts on the plugboard at the control station introduces an error function in the transferral of information which should be avoided. This current leakage, in contact boards as heretofore designed, may appear either as volume leakage through the body of the insulating or plastic material, or as surface leakage between the contacts and becomes a more significant factor should there be flaws or imperfections within the composite structure of the board or an accumulation of film or foreign matter on the surfaces of the board.

A solution is to shield the contacts in the plugboard assembly against current leakage by forming the boards of a conductive material and providing insulation sleeves 10 for the contact elements with board apertures. As a matter of practice, it has been found practicable and desirable to use a composition non-conductive material in the construction of the movable or control panels and then provide these panels with a coating of conductive material 15 so as to insure a positive ground of the front panel and all conductive connections to that panel. Additionally, to isolate the individual connections between control panel plugwires and spring contact members held by the rear panel, interlaced strips of conductive material forming 20 a grid having a plurality of individual compartments have been used and secured to the rear panel of plugboard assemblies to avoid erroneous or faulty information transferral because of current leakage on noninsulated or non-shielded assemblies.

35 Accordingly, it is an object of the present invention to provide in a contact assembly for plugboards and their components a spring contact which assures a clean positive electrical contact.

40 Another object of the present invention is to provide a contact assembly for plugboards wherein the relative movement of the contact carriers is directionally translated into a wiping action between the contacts.

45 A further object of the present invention is to provide in a plugboard assembly a spring contact member to engage a mating plugwire which is simple to insert and lock in position in the associated contact carrier.

50 Still another object of the present invention is to provide in a plugboard assembly a spring contact of a durable single piece construction and simple design.

55 Still another object of the present invention is to provide in a plugboard assembly an improved shielded contact board composition and construction.

Yet another object of the present invention is to provide 60 a plugboard assembly that, when closed and reopened, will automatically clean contact surfaces to insure positive engagement and electrical conduction.

65 Yet a further object of the present invention is to provide in a plugboard assembly a spring contact and associated or mating plugwire that results in a positive electrical connection for associated equipment.

70 Yet still another object of the present invention is to provide a shielded plugwire for use with an improved shielded plugboard assembly of a minimum size so as to allow a greater number of such plugwires to be carried by assembly panels of conventional size than has been heretofore known in the art.

75 These and other objects of the present invention will become apparent to those skilled in the art upon a reading of the following detailed description when taken in conjunction with the drawings in which there is shown

and described a preferred embodiment of the invention; however, it is to be understood that this embodiment is not intended to be exhaustive nor limiting of the invention but is given for purposes of illustration in order that others skilled in the art may fully understand the invention and the principles thereof and the manner of applying it in practical use so that they may modify it in various forms, each as may be best suited to the conditions of a particular use.

In the drawings:

FIG. 1 is a perspective, exploded view of one embodiment of a plugboard assembly particularly illustrating the latching assembly and guide means contained within the rear bay frame for securing positively the front panel frame therein;

FIGS. 2(a) through (e) is a diagrammatic and sequential illustration of the closing operation in four different stages of the front and rear frames of one embodiment of the plugboard assembly through one complete crank cycle;

FIG. 3 is a side elevational, sectional and enlarged view of the spring contact member for use in one embodiment of the plugboard assembly showing the insertion of a barrel support member or insert by a special tool used to insure positive attachment and support of the contact member within a panel wall;

FIG. 4 is a perspective and enlarged view of the inserting tool shown in FIG. 3 used to position the barrel support member within the tubular barrel chamber of the spring contact member;

FIGS. 5(a) through (d) is a diagrammatic sequential portrayal of the closure of the front and rear frame panels which creates a positive physical and electrical contact between the plugwise and the spring contact member;

FIG. 6 is a side elevational, fragmentary, sectional and enlarged view of the rear panel board and the interconnection on its front surface of a lapped-joint grid arrangement constructed from a plurality of conductive copper covered strips of an insulating material;

FIG. 7 is a side elevational, sectional, fragmentary view of the rear panelboard of one embodiment of the plugboard assembly illustrating the attachment of a rear grid to the back surface of the rear panelboard;

FIG. 8 is a perspective, fragmentary view of the grid formed from conductive strips of material to create isolating chambers for assembly conductors illustrating a securing stud attached thereto which normally extends through an aperture in the rear panelboard;

FIG. 9 is a side elevational, sectional, fragmentary and slightly enlarged view of an improved shielded plugwire held within an aperture of a front panelboard of one embodiment of a plugboard assembly;

FIG. 10 is a side elevational, sectional and fragmentary view of a spring contact member secured within an aperture of the shielded plugboard assembly rear panel as shown in FIG. 15 illustrating the positioning of the U-shaped flap within the counterboard portion of the aperture;

FIG. 11 is a side elevational, fragmentary and exploded view of two conductive strips in their inclined angular relationship forming a portion of the insulating grid shown in FIG. 8;

FIG. 12 is a front elevational, fragmentary and sectional view of a rear panelboard containing a plurality of spring contact members having U-shaped supports held within the intersecting recesses etched in the face of that panel;

FIG. 13 is a side elevational, sectional and fragmentary view of the barrel portion of a spring contact member being held within an aperture of the rear panelboard;

FIG. 14 is a rear elevational view of a rear panelboard showing the barrel portion of a plurality of spring contact members being secured against removal by a diverging U-shaped flap attached thereto;

FIG. 15 is a front elevational view of the rear bay panel sustaining a plurality of spring contact members in contact alignment within individual compartments formed by the grid constructed of a plurality of lapped-joint conductive strips;

FIG. 16 is a front elevational view of the panel shown in FIG. 15 having the spring contact members and grid removed to illustrate the counterbored apertures which receive the U-shaped legs of the spring contact member barrel portions; and

FIG. 17 is a sectional view taken along lines 17-17 of FIG. 16 illustrating the depth of the counterbored apertures.

Referring now to the drawings, a fixed plugboard panel frame generally designated 9 holds a plugboard panel 10 of any suitable electrical insulating material generally designated 10 in FIG. 1 which is provided with rows and columns of apertures 12 adapted to receive therein a set of spring contact members 14. As best shown in FIG. 10, contact members 14 are the terminals for the leads which electrically couple the fixed panel to the sensing elements and the operative instrumentalities of the computer or the like (not shown) with which the plugboard assembly is used. Contact members 14 may take any suitable form, but a particular and preferred embodiment best suited for the present plugboard system has been adapted and will be described subsequently in greater detail.

Cooperating with contact members 14 to effect the desired circuit interconnections within the computer or the like are plugwire connectors 16 that are adapted to be received by a plurality of apertures 18 within a front panel board generally designated 20 which is formed of a suitable insulating material and constructed as an integral component of the front panel frame generally designated 21.

To permit the front panelboard 20 (hereinafter referred to as panel 20) to be detached from the entire plugboard assembly, rear panelboard 10 (hereinafter referred to as panel 10) is securely retained by a plurality of retaining rails 22 each of which form a portion of frame 9 and contain a number of contoured recesses 24, 25, and 26 particularly shaped to mate with and receive cooperatively guide members 28, 30 and 32. To attach panel 20 to the rear frame 9 and position that panel in a substantially parallel relationship with panel 10, guide members 28 are directed generally into recesses 24 and particularly into the upper notched indentations 34 which will thus allow panel 20 to be loosely pivotable within the rear frame structure, particularly side rails 22 so that panel 20 is adapted to swing into the face of panel 10 and be juxtaposed with respect thereto. As panel 20 swings into the face of panel 10, guides 30 and 32 are generally received within recesses 25 and 26.

The closure operation of panel 20 with respect to panel 10 and the subsequent latching of these two panels in an interconnected relationship is best illustrated in FIGS. 2(a) through (e). The camming mechanism generally designated 38 is most clearly illustrated in FIG. 1 wherein

there is shown a rod 40 rotatably maintained by side rails 22 forming a portion of rear frame 9. A camming surface 42 is either integrally or separately attached to rod 40 to provide an offset or rise which will subsequently engage the lower edge 44 of frame 21. A contact pin 46 extends perpendicularly from the longitudinal axis of rod 40 and is positioned particularly to limit the rotational movement of rod 40 between prescribed limits. Those limits are controlled by limiting lugs 48 and 50 which extend perpendicularly from the interior wall 51 of a side rail 22 and directly engage contact pin 46 upon rotation of rod 40. A crank arm 52 communicates with rod 40 and is positively secured thereto to permit rotation of rod 40 and its related camming surfaces 42 upon displacement of crank 52.

In FIG. 2(a), the panel 20 has been loosely positioned

so that guide member 28 rests in indentation 34, and a gravity actuated rotation of panel 20 thereabout is effected. As panel 20 pivots about guide member 28, it swings into the face of panel 10 and becomes juxtaposed with respect thereto so that guide members 30 and 32 rest loosely within recesses 25 and 26. Upon gravity actuated rotation of panel 20 into the face of panel 10, the lower edge 44 of front panel 20 rests against the surface 54 of cam 42 as particularly illustrated in FIG. 2(b). Note that crank 52 is in a substantially horizontal position so that contact pin 46 engages limiting lug 50 thus precluding further displacement of crank 52 in a downward direction.

Once panel 20 has been seated in a substantially parallel position with respect to panel 10, crank 52 can be rotated since this will in turn revolve rod 20 and slide camming surface 42 against the lower edge 44 of panel 20. As the cams highest surface 56 is at a location which would contact edge 44 of panel 20 when crank arm 52 is in a substantially vertical position, the gradual displacement of crank 52 toward the vertical position will gradually elevate panel 20 with respect to panel 10 and cause the respectively related and carried plug wires and spring contact members to become engaged positively for electrical connection, an operation which will be described in greater detail subsequently. Note in FIG. 2(c) that as panel 20 is elevated, guide members 30 and 32 have commenced to enter grooves 58 and 60 extending from recesses 25 and 26 which act as guide means to induce selected movement of panel 20 with respect to panel 10 when crank 52 is displaced. Complete displacement of crank 52 to a substantially vertical position as shown in FIG. 2(e) urges panel 20 to a maximum height with respect to panel 10 and wedges guide means 30 and 32 securely into recesses 58 and 60 so that frames 9 and 21 cannot be inadvertently displaced each from the other. Note that as panel 20 is lifted by the action of camming surface 42 revolving with rod 40, guide member 28 which was used initially to loosely connect and pivot panel 20 with respect to panel 10 is lifted from recess 34 and plays no part in retaining the respective frames in an interconnected relationship. Only when crank 52 is shifted downwardly from the vertical position to a substantially horizontal position as shown in FIG. 2(a) does guide member 28 again come into play because of the gravity actuated displacement of panel 20 downwardly to disengage guides 30 and 32 from recesses 58 and 60.

The physical and electrical connections made between plugwires 16 and spring contact members 14 when a plurality of these components are retained within apertures 12 and 18 of panels 10 and 20 is sequentially and diagrammatically illustrated in FIGS. 5(a) through (d). These sequential diagrams are positioned to illustrate particularly the action of a spring contact member 14 and a plugwire 16 when panel 20 is moved with respect to panel 10 as shown in FIGS. 2(b) through (e). For example, when panel 20 has become substantially parallel with panel 10 as shown in FIG. 2(b), the relationship between all spring contact members 14 and plugwires 16 are as particularly illustrated in FIG. 5(a) which is situated directly below the panel positioning drawing above described. As crank 52 is displaced to approximately an incline of 45 degrees with the horizontal, panel 20 shifts upwardly as shown in FIG. 2(c) and plugwire 16 lifts to engage the lower tip 62 of the contact portion generally designated 64 of member 14. As crank 52 continues toward the substantially vertical position it occupies when frame 21 is securely locked into position with respect to the frame 9, plugwire 16 continues to ride upwardly against the narrow contacting surface 66 of the contact portion 64 of spring 14. When crank 52 has been secured in the vertical position as shown in FIG. 2(e), plugwire 16 has slidably moved against the narrow contact surface 66 of portion 64 to a high position along that surface where it will be maintained in a secure fashion for positive electrical con-

75

nnection. Thus it can be seen that contact surface 66 of spring 14 can be made completely dust free and current receptive by one or two cycles or repetitions of operation of crank 52 since lifting crank 52 from a horizontal to a vertical position will cause plugwire 16 to ride against contact surface 66 from its lowermost point to an upper position thereon and thus wipe and clean the metal surface in a firm manner. When crank 52 is lowered, plugwire 16 moves back over the previously wiped surface to a disengaged position as shown in FIG. 5(a). Any number of such operations can be effected to insure absolutely clean contact surfaces and troublefree electrical connections.

When crank arm 52 is moved from the horizontal to the substantially vertical position substantially parallel to side rail 22, it is releasably secured to that rail by means of a ball 68 revolvably positioned in a housing 70 which in turn is secured to rail 22 by any suitable means. Crank 52 has on its interior surface 72 a recess 74 for receiving ball 68 when lever 52 is in an upright position in alignment therewith. The securement of lever 52 avoids an accidental displacement of that lever which might allow panel 20 to become disengaged from panel 10.

Plugwire 16 can be of any conventional manufacture, however, best results have been achieved when a wire such as described and disclosed in my pending application Ser. No. 412,447 is used, this being of a conventional non-shielded construction best suited for ordinary and normal operation. To suit particular applications and needs, a shielded plugwire has been devised which is suggested for use with the shielded plugboard assembly subsequently to be described that occupies approximately one-half the surface area heretofore required when using shielded plug contractors. My shielded plugwire as illustrated in FIG. 9 is comprised of an inner conductor member 76 which has as integrally affixed contact tip 78 extending from the leading or forward end and a suitable shielded wire 80 secured to the rearward end of that member. An insulating sleeve 82 surrounds conductor member 76 so as to preclude any physical contact or electrical continuity by another metallic object with that member while it is surrounded by the sleeve. A grounding shield 84 surrounds conductor member 76 and insulating sleeve 82 and extends rearwardly to connect with wire shield 83 of conductor 80. A suitable covering 86 of vinyl or other desirable material encloses the rear portion of grounding shield 84 and the junction of that shield with the grounded or shielded cover 83 of conductor 80. Shield 84 is particularly constructed with a plurality of extending, resilient, and flexible fingers 87 which lock the plugwire 16 releasably within aperture 18 of panel 20 and assure that a uniform system ground is achieved. When plugwire 16 is inserted into an aperture 18, fingers 87 are pressed inwardly to allow movement of a plugwire into a board aperture. Once seated therein, ridges 89 prevent accidental removal of the plugwire from the panel.

Spring contact member 14 is comprised of a barrel portion generally designated 90 which is adapted to be received by apertures 12 in panel 10 of rear frame 9, and a barrel insert 92 which is received within barrel portion 90 secures contact member 14 in a pre-selected position within an aperture 12 in panel 10. FIGS. 3 and 4 illustrate the injection of barrel insert 92 by means of a tool 94 which is not included as a part of the present inventive concept, but which functions to position inserts 92 when rotated approximately 180 degrees. A leaf-spring portion 96 integrally extends from barrel portion 90 and supports a contact portion 64 substantially formed in a V-shaped fashion to provide a rib having a narrow contact surface 66 which mates with the contact tip 78 of plugwire 16. The natural resiliency of spring portion 96 allows that member to flex as plugwire 16 is moved thereagainst and upwardly as previously described and portrayed in FIGS. 5(a) through (d). A reinforced belly 100 is crimped within spring 14 at the junction of barrel portion 90 and spring portion 96 to provide additional strength between

these components and to withstand the numerous movements of spring 96 with respect to barrel 90 when plugwire 16 is continuously urged thereagainst and subsequently removed.

Spring members 14 are secured within apertures 12 of panel 10 in a particular fashion in order to insure that they will remain in fixed and immovable when exposed to the continued physical connection of associated and interconnecting plugwires 16. The forward end of the barrel portion 90 generally designated 102 is constructed in a U-shaped manner so that the legs 104 can be securely imbedded within the plurality of intersecting grooves 106 or on the front surface of panel 10, thus precluding any rotational movement of member 14 within aperture 12 of panel 10. It has been found advantageous to seat spring members 14 in alternate directions (see FIGS. 12 and 15) so as to uniformly distribute the force exerted by the spring 14 against the contact pin 78 of plugwire 16 when panel 20 is urged against panel 10 and the contact members 14 and plugwires 16 become interconnected.

The rearward portion 107 of panel 10 is essentially smooth and a second U-shaped member 108 integral with barrel portion 90 of spring member 14 can be expanded in a diverging manner so as to preclude a removal of member 14 by inadvertent or accidental pulls or blows.

It is, of course, understood that the assembly previously described is completely effective for use in unshielded systems when using a conventional plugwire rather than the shielded or insulated plugwire hereinabove described. As computer technology advances and current and voltage ratings become more and more critical, it is desirable and essential to avoid any unbalancing characteristics by the use of totally shielded systems. It has consequently been found desirable to provide the assembly hereinabove described with shielding means so as to completely isolate individual conductors and establish a uniform and consistent ground throughout the entire system.

Panel 10 is particularly constructed for use in a shielded system by assembling a plurality of conductive strips such as shown in FIG. 11 and designated 110 and 112 which are constructed with a plurality of slots 114 so that they might be intermated to form a grid generally designated 115 (FIG. 8) having individual compartments 116, each surrounding a conductor assembly such as is shown in FIG. 5(d) which will be subsequently described. Strips such as those designated 110 and 112 are covered with a conductive material so that upon intermatting with each other, they become a continuous conductor which may be secured to the system ground and provide a uniform neutral or ground potential for computer operation. The grid defined by the intermeshing of a number of conductive strips such as 110 and 112 then forms rows and columns of compartments 116 on the front 117 of panel 10 which will house the spring contact members 14 within for subsequent mating with plugwires 16. Upon the assembly of a number of conductive strips 110 and 112 to form the grid as shown in FIG. 8, several securing studs generally designated 118 which extend through aperture 12 and engage the grid 115 at a junction 122 where it is subsequently soldered to insure against separation and displacement. The X-shaped slots 124 are carried on the grid-engaging portion generally designated 125 of stud 118 while a flange 126 extends rearwardly of the stud to preclude its inadvertent movement from aperture 12 of panel 10. A connector 128 can then be secured within aperture 130 of stud 118 to permit attachment of a conductor or ground wire 132 extending to the system neutral or ground. It has been found advantageous to arrange a pattern of studs 118 uniformly throughout selected perforations of panel 10 in order to insure a consistent ground attachment with the grid formed by conductive strips such as designated 110 and 112.

A somewhat thinner grid 136 shown in FIGS. 7 and 15 is formed from a plurality of conductive strips similar to

those disclosed in FIGS. 6, 8 and 11 and designated 110 and 112 in FIG. 15 to cover the rearward portions 108 of spring members 14 as they extend from the back surface 107 of panel 10 for securement to a plurality of conductors (not shown). As this conductor-spring contact member junction is essentially of a nonsymmetrical and non-uniform configuration, better results are obtained if these junctions are also shielded within individual compartments formed from the interconnection of a number of conductive strips forming a grid. Again, additional grid securing studs generally designated 134 extend through aperture 12 of panel 10 as shown in FIG. 7 to attach the thinner grid generally designated 136 to the rear side 107 of the panel. The height of grid 136 formed of the intermeshing conductive strips on the rear side 107 of panel 10 does not equal the height of grid 115 attached to the front surface 117 of panel 10 covering the interconnection of plugwires and spring contact members. Since the conductor connection is made closely adjacent the rear surface of rear panel 10, the shield formed from the assembled grid 136 need not extend away from surface 107 of panel 10 to any great degree.

Upon interconnection of front panel 20 with rear panel 10 their carried components, namely plugwires 16 and spring contact members 14, the assembled grid 115 surrounding the connecting plugwires and contact members occupies substantially the majority of space between panels 20 and 10. It has been found advantageous to produce strips such as those designated 110 and 112 from a nonconductive plastic material and then coat these strips with copper or some other suitably conductive material to provide the necessary conductivity and to conserve weight and expense experienced in the use of conventional solid materials.

It has also been found advantageous to use a conventional composite phenolic for panel 20 and simply to coat this panel uniformly even to the extent of coating the interior walls of apertures 18 with a similarly conductive material to provide a uniform system ground or neutral.

While in the foregoing specification and drawings I have shown and described a preferred embodiment of my invention, it will be recognized by those skilled in the art that many modifications and variations may be made in the construction and arrangements of the front and rear panels, the assembled grids, the spring contact members and the plugwire connectors as well as other phases of the present inventive concept in light of the above teachings without departing from the real spirit and purpose of this invention. Such modifications of parts and alternatives as well as the use of mechanical and electrical equivalents to those herein illustrated and described are reasonably included and modifications are contemplated.

What is claimed is:

1. A multiple-contact interconnecting plugboard assembly for a patchcord system comprising: a rear bay with a plurality of apertures and diagonal grooves intersecting said apertures, said bay carrying a plurality of spring contact members having leg means resting in said diagonal grooves to non-rotatably secure said spring members therein; a front bay with a plurality of plugwire receiving apertures, said bay being removably pivoted on said rear bay and having a plurality of plugwire members removably positioned in said plugwire receiving apertures and adapted to engage said spring contact members upon interconnection of said assembly, said front bay being adapted to be swingably juxtaposed with said rear bay with said plugwire members spaced from said spring contact members by a given distance to permit bay closure; camming means movably secured to said rear bay and operable to urge said front bay upwardly a vertical distance greater than said given distance to cause said plugwire members to bear against said spring contact members and effect contact therebetween; a crank arm communicating with said camming means and adapted to pivot between preselected limits, said camming means being

responsive to pivotal movement of said arm; guide means carried by said rear bay to direct said front bay upwardly with respect thereto following operation of said camming means while maintaining said rear and front bays at a constant spaced-apart relationship sufficient to allow contact between said spring contact and plugwire members; and means for releasably securing said crank arm upon rotation of said camming means to retain said front and rear bays in said spaced relationship and maintain said plugwire members in engagement with said spring contact members.

2. A multiple-contact interconnecting plugboard assembly as set forth in claim 1, said camming means including a control rod rotatably maintained by said rear bay having (a) dual camming surfaces formed thereon, a contact pin extending perpendicularly from the longitudinal axis of said rod adjacent one side of said rear bay and first and second limiting lugs secured to one side of said rear bay and positioned to restrict rotation of said rod camming surface between limits by said first lug engaging said contact pin when said plugwire members are spaced from said pin members by a given distance upon juxtaposition of said bays and said second lug engaging said contact pin when said front bay is urged upwardly and said plugwire members have moved to engage said spring members and effect contact therebetween.

3. A multiple-contact interconnecting plugboard assembly for a patchcord system as set forth in claim 1, said guide means including three recesses on each side of said rear bay and (a) three complementing lugs projecting from each side of said front bay to mate within said recesses and induce preselected pivotal and slidable movement of said front bay with respect to said rear bay upon operation of said camming means, said recesses and complementing lugs precluding disengagement of said plugwire members with said spring members until said camming means allows movement by said guide means of said front bay downwardly with respect to said rear bay to disengage said members.

4. A multiple-contact interconnecting plugboard assembly for a patchcord system as set forth in claim 2, said guide means including three recesses on each side of said rear bay and (a) three complementing lugs projecting from each side of said front bay to mate within said recess and induce preselected pivotal and slidable movement of said front bay with respect to said rear bay upon operation of said camming means, said recesses and complementing lugs precluding disengagement of said plugwire members with said spring members until said camming means allows movement by said guide means of said front bay downwardly with respect to said rear bay to disengage said members.

5. A multiple-interconnecting plugboard assembly for a patchcord system as set forth in claim 1, each of said spring contact members comprising a barrel portion having a detent and adapted to be received by one of said rear bay apertures for mounting said member on said plugboard, a leaf spring portion integrally extending from said barrel portion, a contact portion integral with said spring portion forming a rib to provide a narrow contact surface, and a barrel insert having a circumferential recess, said insert extending within said barrel portion to support and secure said spring contact member in a preselected position on said rear bay.

6. A multiple-interconnecting plugboard assembly for a patchcord system as set forth in claim 4, each of said spring contact members comprising a barrel portion having a detent and adapted to be received by one of said rear bay apertures for mounting said member on said plugboard, a leaf spring portion integrally extending

from said barrel portion, a contact portion integral with said spring portion forming a rib to provide a narrow contact surface, and a barrel insert having a circumferential recess, said insert extending within said barrel portion to support and secure said spring contact member in a preselected position on said rear bay.

7. A multiple-contact interconnecting plugboard assembly for a patchcord system as set forth in claim 1, said rear bay being of an insulating material and carrying a plurality of grounded conductive strips assembled in the form of a grid to form individual compartments surrounding and shielding said spring members.

8. A multiple-contact interconnecting plugboard assembly for a patchcord system as set forth in claim 6, said rear bay being of an insulating material and carrying a plurality of grounded conductive strips assembled in the form of a grid to form individual compartments surrounding and shielding said spring members.

9. A multiple-contact interconnecting plugboard assembly for a patchcord system according to claim 7, said front bay having a conductive grounded surface coating uniformly distributed thereover.

10. A multiple-contact interconnecting plugboard assembly for a patchcord system according to claim 8, said front bay having a conductive grounded surface coating uniformly distributed thereover.

11. A multiple-contact interconnecting plugboard assembly for a patchcord system according to claim 9, each of said plugwires having an inner conductor member, an insulating sleeve surrounding said conductor member and adapted to insulate inner conductor member from said front bay conductive coating, and a grounding shield substantially enveloping said sleeve and conductor member to position shield and ground said plugwire with respect to said front bay conductive surface.

12. A multiple-contact interconnecting plugboard assembly for a patchcord system according to claim 10, each of said plugwires having an inner conductor member, an insulating sleeve surrounding said conductor member and adapted to insulate inner conductor member from said front conductive coating, and a grounding shield substantially enveloping said sleeve and conductor member to position shield and ground said plugwire with respect to said front bay conductive surface.
